CLAIM

The ornamental design for the expandable frame for prosthetic heart valve as shown and described.

DESCRIPTION

FIG. 1 is an enlarged perspective view of an expandable frame for prosthetic heart valve in a configuration where the ends are connected in accordance with the new design;

FIG. 2 is another enlarged perspective view of the expandable frame for prosthetic heart valve thereof;

FIG. 3 is a front view of the expandable frame for prosthetic heart valve of FIG. 1 in a configuration where the two ends are not connected; and,

FIG. 4 is an enlarged left side view of the expandable frame for prosthetic heart valve thereof.
